UNITED STATES PATENT OFFICE.

FRANK TORRE, OF NEWARK, NEW JERSEY, ASSIGNOR TO T. & T. TOY CO., OF NEW YORK, N. Y., A FIRM CONSISTING OF FRANK TORRE AND SETTIMO FIDONA.

DESIGN FOR A LAMP.

Application filed July 22, 1922. Serial No. 3,176. Term of patent 3½ years.

To all whom it may concern:

Be it known that I, FRANK TORRE, a citizen of the United States, residing at Newark, in the county of Essex and State of New Jersey, have invented a new, original, and ornamental Design for Lamps, of which the following is a specification, reference being had to the accompanying drawing, forming a part thereof.

In said drawing, the figure illustrates in perspective an ornamental lamp embodying the features of my novel design.

I claim:—

The ornamental design for a lamp, as shown and described.
